Des. 181,760

Patented Dec. 17, 1957

181,760

PIVOTAL GAME CARD AND CHIP HOLDER

Ruth M. Swenson, Great Falls, Mont.

Application June 18, 1956, Serial No. 41,945

Term of patent 14 years

(Cl. D34—13)

FIG. 1

FIG. 2

FIG. 3

FIG. 4

FIG. 5

FIG. 6

Fig. 1 is a perspective view of a pivotal game card and chip holder showing my new design in an angular position;

Fig. 2 is a left side elevation of Fig. 1 showing the pivotal game card and chip holder in rectilinear position;

Fig. 3 is a right end elevation of Fig. 2;

Fig. 4 is a top plan view of Fig. 2;

Fig. 5 is a left end elevational view of Fig. 2; and

Fig. 6 is a bottom plan view of Fig. 2.

I claim:

The ornamental design for a pivotal game card and chip holder, substantially as shown.
